PREPARATION OF ALKYL ARYL SULFONATES OF REDUCED VISCOSITY

Max T. Nigh, San Pablo, Calif., assignor to California Research Corporation, San Francisco, Calif., a corporation of Delaware

No Drawing. Application June 24, 1950,
Serial No. 170,255

2 Claims. (Cl. 252—161)

This invention relates to new and useful hydrocarbon compositions suitable for conversion to magnesium alkyl benzene sulfonate detergents and, in particular, it relates to improved alkyl benzene hydrocarbon mixtures suitable for the production of improved low viscosity slurries of such detergents.

Magnesium alkyl benzene sulfonate detergents represent an important group in the class of alkyl aryl sulfonate detergents. They are prepared by condensing (alkylating) benzene with an olefin, an olefin polymer, or an alkyl halide to form mixtures of long-chain monoalkyl benzene hydrocarbons containing from 10 to 18 carbon atoms in the alkyl chain, sulfonating the mixture, and neutralizing the resulting alkyl benzene sulfonic acids with a slurry of an alkaline magnesium compound to obtain a final aqueous slurry of magnesium monoalkyl benzene sulfonates suitable for eventual processing to produce a solid, particle-form detergent material.

However, heretofore, it has been considered an impossibility to prepare such aqueous slurries having a solid content of magnesium alkyl benzene sulfonate detergent in excess of 40% by weight, without encountering serious difficulties in handling the slurries, owing to the high viscosity which interferes with pumping and flow of these materials through the lines of the processing plant. Magnesium alkyl benzene sulfonate detergent slurries having a solid content in excess of 45% are so viscous that they cannot be handled through the lines in the plant with the aid of conventional pumping machinery. Dilution with water to a consistency suitable for unimpeded transfer through the lines by conventional pumping equipment is uneconomical; furthermore, when the slurry is thus greatly diluted with water, the product resulting upon reduction of the slurry to the solid form, e. g., to beads by spray-drying, is less satisfactory. The beads are friable and possess a low tensile strength, which fact contributes to the formation of fines and irritating dust. Moreover, a higher consumption of fuel and energy is necessary to effect evaporation of the water of dilution from the magnesium alkyl benzene sulfonate slurry. When the diluted slurries are shipped to a processing plant by tank car, the freight charges are substantially increased by the presence of an excess of water.

I have now found that the addition of a minor amount of a low molecular weight mononuclear aromatic hydrocarbon boiling in the range from about 179° F. to about 400° F. to the long-chain monoalkyl benzene prior to sulfonation secures remarkably reduced viscosities in magnesium monoalkyl benzene sulfonate detergent slurries upon eventual sulfonation of the monoalkyl benzene base-stock so diluted, and subsequent neutralization of the sulfonated product mixture with an alkaline magnesium compound.

The viscosity of detergent slurries derived from monoalkyl benzene containing the low molecular weight aromatic hydrocarbon in accordance with my invention is usually equal to less than 100 poises at 135° F. (Brookfield viscometer at 10 R. P. M.) as compared with the

2

viscosities in excess of 1000 poises at 135° F. observed for the detergent slurries derived from the same monoalkyl benzene containing no added low molecular weight aromatic hydrocarbon. The slurries produced from 5 monoalkyl benzene containing a minor amount of such a low molecular weight mononuclear aromatic hydrocarbon additive can be handled through conventional pumping equipment and pipe-lines without difficulty, although these slurries contain 40, 50 and even as much as 55 percent by weight of solids.

The mixture containing the added low molecular weight mononuclear aromatic hydrocarbon can be sulfonated by any conventional method, e. g., with the aid of sulfuric acid, oleum, or SO_3 , and the sulfonation product is then 15 neutralized with a slurry of a magnesium alkaline compound, e. g., magnesium oxide and magnesium hydroxide. After sulfonation with sulfuric acid, preferably fuming acid, or with sulfur trioxide, the sulfonation reaction mixture is settled to permit separation and withdrawal of the 20 excess of sulfuric acid. In most cases, upon settling and removal of excess sulfuric acid, the sulfonation product will contain from 80 to 90% sulfonic acid and this concentrated sulfonic acid is reacted with the magnesium alkaline compound. The final neutralized pumpable 25 slurry of magnesium sulfonate detergent which may contain a minor amount of magnesium sulfate formed by neutralization of residual sulfuric acid may then be pumped through connecting lines to an appropriate treating unit where it will be reduced to the particulate solid form, e. g., by spray-drying. When magnesium carbonate is the neutralizing agent for the sulfonation reaction product, the conditions of neutralization will be modified in accordance with the conventional practices of those skilled in the art.

30 The low molecular weight mononuclear aromatic hydrocarbon to be added to the base stock of monoalkyl benzene is selected from the group of low molecular weight mononuclear aromatic hydrocarbons boiling in the range from about 179° F. to about 400° F. These 35 mononuclear aromatic hydrocarbons comprise benzene and the various readily sulfonatable monoalkyl and dialkyl substituted benzenes containing an aggregate of not more than 5 alkyl carbon atoms. The term "alkyl carbon atoms" as employed in this specification hereinafter 40 shall mean carbon atoms present in the alkyl chain or chains of an alkyl aromatic hydrocarbon having one or more alkyl side chains. The mononuclear, monoalkyl and dialkyl hydrocarbons contemplated as operative additives to long-chain monoalkyl benzene base-stock for the 45 eventual preparation of alkyl benzene sulfonate detergents include toluene; xylenes; ethyl benzene; diethyl benzenes; ethyl methyl benzenes; cumene; ethyl propyl benzenes; methyl butyl benzenes; butyl benzenes; propyl benzenes; and the like, as well as mixtures of such monoalkyl and 50 dialkyl benzenes containing an aggregate of not more than 5 alkyl carbon atoms per molecule. For instance, mixtures of xylenes produced in the hydroforming treatment of petroleum fractions may be successfully used.

Ordinarily these low-boiling, low-molecular weight aromatic hydrocarbons are added in amounts ranging from 60 about 0.5 to about 5.0% by weight of the base-stock, although higher amounts will also be operative. In some cases, somewhat lower amounts of the diluent will be effective; thus, an addition of as little as 0.3% by weight 65 of a xylene is found to be sufficient to secure the desired reduction in viscosity. For practical purposes, however, the preferred range of low-boiling alkyl aromatic hydrocarbon additions to the base-stock lies between about 1.0 and about 3.0% by weight.

70 All of these low molecular weight mononuclear aromatic hydrocarbons, when added in minor amounts as specified hereinbefore to the base-stock of C_{10} to C_{18}

monoalkyl benzenes, undergo the same reactions of sulfonation and neutralization as the base-stock containing them and are finally converted to the corresponding magnesium salts of benzene sulfonic acids, e. g., magnesium mono- and dialkyl benzene sulfonates, containing and aggregate of less than about 6 alkyl carbon atoms. The relative proportions of these magnesium sulfonates in the slurry of magnesium alkyl benzene sulfonate detergent containing from 10 to 18 carbon atoms in the alkyl chain may range from about 0.6 to about 6.0%, and preferably from about 1.2 to about 3.5%, based on the weight of the active magnesium alkyl benzene sulfonate detergent, in order to insure a pumpable viscosity equal to 100 poises or less at 135° F. of the detergent slurry.

The base stock for the preparation of magnesium C₁₀ to C₁₈ alkyl benzene sulfonate slurries of my invention may be taken among a variety of alkyl benzene hydrocarbons with an alkyl chain containing from 10 to 18 carbon atoms. Suitable alkyl benzenes may be produced by alkylation of benzene with olefins containing from 10 to

The viscosity in all instances was less than about 100 poises at 135° F. (Brookfield viscometer at 10 R. P. M.).

The remarkable reduction of viscosity secured by my invention may be seen from the following Table I, in which are tabulated the results of viscosity determinations made with the aid of a Brookfield viscometer on a number of slurries having a solid content of about 52 to 53% magnesium alkyl benzene sulfonate detergent derived from various base-stocks of a representative alkyl benzene having from 12 to 15 carbon atoms in the alkyl chain, to which minor amounts of a low molecular weight mononuclear aromatic hydrocarbon were added in accordance with my invention. The average extent of sulfonation was about 98%, approximately 1.5-2.0% of hydrocarbon oil remaining unsulfonated. The table shows that the addition of such low boiling aromatic hydrocarbons in the previously mentioned preferred range from about 1.0 to about 3.0%, based on the weight of the base stock, radically reduces the viscosity of the ultimately produced magnesium alkyl benzene sulfonate detergent slurry.

TABLE I

Effect of addition of a low molecular weight mononuclear aromatic hydrocarbon to representative C₁₂-C₁₅ alkyl benzene base-stocks on viscosity of ultimate magnesium alkyl benzene sulfonate detergent slurries

Run No.	Composition (Base-Stock+Additive)	Percent Weight Additive	Neutralized and Sulfonated Percent by Wt. Based on Total Mixture of Detergent and Additive	Viscosity at 135° F. after Settling for 24 hours (Brookfield Viscometer at 10 R.P.M.) in Poises
1	Alkyl Benzene Base-Stock "A" boiling from 511-575° F.			>1,000
2	Alkyl Benzene Base-Stock "B" boiling from 508-590° F.			>1,000
3	Alkyl Benzene Base-Stock "A"+Tertiary Butyl Benzene	1.0	1.23	91
4	do	0.5	0.61	102
5	Alkyl Benzene Base-Stock "A" + Xylene	1.5	2.03	54
6	do	0.5	0.68	68
7	Alkyl Benzene Base-Stock "B"+Mixture of Predominantly Xylene Hydrocarbons from Hydroforming Treatment of Petroleum.	3.0	3.73	47.5
8	Alkyl Benzene Base-Stock "B"+Benzene	3.0	4.7	75.0

18 carbon atoms, and preferably from 12 to 15 carbon atoms, or with olefins produced by the Fischer-Tropsch synthesis. Thus, stocks boiling within the range from about 475° F. to about 650° F. and obtained by condensation of benzene with propylene polymers containing from 10 to 18 carbon atoms, and preferably from 12 to 15 carbon atoms, in the presence of alkylation catalysts such as H₂SO₄, AlCl₃ or HF, may be used.

Alkyl benzenes obtained by alkylation of benzene with normal butene polymers containing from 12 to 18 carbon atoms, may also be used as base-stocks. Likewise, the so-called "keryl benzenes" produced by alkylation of benzene with a chlorinated kerosene fraction and containing from 10 to 18 carbon atoms, and preferably from 12 to 15 carbon atoms, in the alkyl chain, also represent suitable base-stocks which, upon the addition of a low molecular weight mononuclear aromatic hydrocarbon in accordance with my invention, may be processed to produce a pumpable low viscosity magnesium alkyl benzene sulfonate detergent slurry.

The reduction in viscosity of a magnesium alkyl benzene sulfonate detergent slurry in accordance with the invention is particularly pronounced when sufficient time has been allowed for the neutralized slurry to settle upon neutralization and to release the air enclosed in the fresh slurry. Low-viscosity detergent slurries with densities ranging from 6.5 to about 8.5 pounds per gallon were obtained upon addition from about 0.5 to about 5.0% by weight of an effective low molecular weight mononuclear aromatic hydrocarbon to a monoalkyl benzene base-stock containing from 10 to 18 carbon atoms in the alkyl chain.

Tests were made to ascertain whether or not the addition of a low molecular weight mononuclear aromatic hydrocarbon to the base-stock of a C₁₀ to C₁₈ monoalkyl benzene would affect the performance of the ultimate magnesium alkyl benzene sulfonate detergent product.

Detergency, foaming and wetting power of a representative sample of a magnesium alkyl benzene sulfonate detergent derived from a mixture of monoalkyl benzenes having from 12 to 15 carbon atoms in the alkyl chain, to which xylene has been added in an amount of 1.5% by weight in accordance with the invention, were compared with detergency, foaming and wetting power of a magnesium alkyl benzene sulfonate detergent derived from an identical base-stock, but in the absence of xylene. The base-stock for this detergent was produced by alkylation of benzene with tetramers and pentamers of propylene, and the results of these tests are shown in Table II.

The detergency values in Table II were determined by launderometer tests. Uniformly soiled swatches of cotton were subjected to a series of four consecutive washings in solutions of magnesium alkyl benzene sulfonate detergent of different concentrations (0.1, 0.15, 0.2, 0.3%), the hardness of water being 300 parts per million.

The soil to be removed was uniformly applied to the cotton swatches as a paste made of oil, tallow and carbon black. The tests were effected under conditions usually prevailing in common laundering processes, the procedure being standardized to give reliable results comparable with the actual practice. The temperature employed in these tests was about 140° F. Detergency

ratings were computed with reference to an arbitrarily chosen standard, namely, a whiteness level, or detergency, obtainable with the 0.4% concentration of a well-known household soap in hard water (300 p. p. m.), designated as the Soap Index and assumed to equal 100.

Foam heights were determined in accordance with the standard procedure of the Ross and Miles Tests, described in "Oil And Soap," vol. 18, p. 99, (1944). The concentration of detergent in these foam height determinations was 0.1% with varying amounts of lard oil added to the aqueous detergent solution. Wetting times were determined by the Draves method (using a 3 g. hook), both in distilled water and in hard water, for two different concentrations of detergent (0.05 and 0.1%).

TABLE II

Comparison of surface-active properties of magnesium sulfonate detergent slurry derived from C₁₂ to C₁₅ alkyl (polypropylene) benzene with and without addition of xylene

Detergency	Concen- tration of Detergent in Percent	Base Stock	Base-Stock +1.5% Xylene

The test data tabulated above conclusively indicate that the detergency, foaming and wetting of the low-viscosity sulfonate detergent, produced from the base stock to which a low molecular weight mononuclear hydrocarbon has been added in accordance with my invention, are substantially equivalent to the detergency, foaming and wetting of a high-viscosity sulfonate detergent produced from the base-stock which contained no low molecular weight mononuclear aromatic hydrocarbon additive.

In conclusion, it should be understood that the aforesigned description and the experimental data are illustrative only, and that any variation or modification of my invention which conforms with the spirit and the scope thereof should be included within the terms of the appended claims.

This application is a continuation-in-part of my application Serial No. 167,697 filed June 12, 1950, and now abandoned.

20 I claim:

1. A sulfonatable hydrocarbon mixture comprising polypropylene benzene having from 12 to 15 carbon atoms in the polypropylene group and about 1.5% by xylene.

25 2. A process for producing detergent slurries of reduced viscosity having a solids content of in excess of 40% by weight and containing a magnesium monoalkyl benzene sulfonate as the active detergent ingredient which comprises cosulfonating a mixture of polypropylene benzenes having from 12 to 15 carbon atoms in the polypropylene group and about 1.5% by weight of xylene, neutralizing the sulfonation product mixture with a slurry of an alkaline magnesium compound and recovering a pumpable slurry of the magnesium alkyl benzene sulfonates.
